Primary Examiner — Natasha Vujcic(57) **CLAIM**

The ornamental design for a LED linear high bay light, as shown and described.

DESCRIPTION

FIG. 1 is a perspective view of a LED linear high bay light showing my new design;

FIG. 2 is a front elevation view of the LED linear high bay light of FIG. 1;

FIG. 3 is a rear elevation view of the LED linear high bay light of FIG. 1;

FIG. 4 is an enlarged left-side elevation view of the LED linear high bay light of FIG. 1;

FIG. 5 is an enlarged right-side elevation view of the LED linear high bay light of FIG. 1;

FIG. 6 is a top plan view of the LED linear high bay light of FIG. 1;

FIG. 7 is a bottom plan view of the LED linear high bay light of FIG. 1;

FIG. 8 is an enlarged view of a portion of FIG. 1; and,

FIG. 9 is another enlarged view of the portion of FIG. 1. The break lines in the drawings indicate that the appearance of any portion of the LED linear high bay light between the break lines forms no part of the claimed design.
